Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,296,489.

Specification of Letters Patent.

Patented Mar. 4, 1919.

Application filed October 15, 1918. Serial No. 258,171.

To all whom it may concern:

Be it known that I, FRANK DUTCHER, a citizen of the United States, residing at Versailles, in the county of Allegheny and

- 5 State of Pennsylvania, have invented certain new and useful Improvements in Railway Signal-Torpedoes, of which the following is a specification, reference being had therein to the accompanying drawing.
- 10 This invention relates to improvements in railway signal torpedoes, and the explosive inclosing case is composed of paper or other suitable fibrous material, whereby a non-flying torpedo is provided to prevent flying
- 15 particles which will injure persons who might happen to be near the exploded torpedo.

The object of the present invention is to make a cheap paper or fibrous torpedo of a button-shape, and so constructed that the joints of the case are water-tight and water-proof.

In the accompanying drawings—

25 Figure 1 is a perspective view of a torpedo embodying my invention, the same being shown attached to the tread of a railroad rail.

Fig. 2 is a transverse vertical central sectional view of Fig. 1.

30 Fig. 3 is a sectional view of the parts shown in their disassembled relation and forms.

In carrying out my present invention, I employ a shallow cup-shaped member 1, in which an approximately button shaped explosive tablet 2 is placed, thus forming the tablet with a rounded top ending in a tapered peripheral edge 3. This button-shaped explosive 2, is placed within the case 1, and a dome-shaped disk or cover 4 placed thereover. These members 1, 2 and 4 are then placed within and are inclosed by the outer cup-shaped member 5, which performs the double function of holding the rail-attaching strap 6, and of uniting the parts together, as will be presently explained.

These parts 1, 2, 4 and 5, are assembled as shown in Fig. 2, the cup-shaped member 5 being considerably deeper than the shallow-cup-shaped member 1. Preferably the rail-engaging strap 6 is passed or threaded through openings 7 in the outer case 5 before the parts are assembled.

In assembling the parts, the shallow cup-shaped member 1 is placed within the rela-

tively deeper cup-shaped member 5; the explosive 2 is placed within the shallow cup-shaped member 1, and the dome-shaped top or cover 4 is placed over the explosive 2 and within the cup-shaped member 1. With the 60 parts thus assembled, the peripheries 8 and 9 of the members 5 and 1 are crimped inward tightly over the dome-shaped top 4, with the peripheral wall 8 lapping over and beyond the peripheral wall 9. These crimped 65 in flanges or walls 8 and 9 are cemented in their crimped position by cement 10.

The cup-shaped members 5 and 1 and the dome-shaped member 4 are composed of water-proof paper or fiber, for the purpose 70 of protecting the explosive, 2, from moisture, and the cement 10 is composed of water-proof cement so that the torpedo when completed is water-tight and water-proof.

It will, of course, be understood that in 75 the assembling of these parts, the explosive 2 and dome-shaped top 4 may be placed within the cup-shaped member 1, and the flange 9 crimped thereover before it is placed within the cup-shaped member 5. In this 80 instance, the flanges 8 and 9 will be separately crimped instead of being crimped together.

Having thus described my invention, what I claim and desire to secure by Letters Patent is:—

1. A fibrous water-proof non-flying railway signal torpedo, comprising a fibrous cup-shaped case, a button-shaped explosive tablet within the case, a dome-shaped top 90 fitting within the case and inclosing the tablet, the side wall of the cup-shaped case crimped inward and water-proof cemented to the said dome-shaped top throughout its periphery.

2. A fibrous water-proof non-flying railway signal torpedo, comprising inner and outer fibrous cup-shaped cases, the side wall of the outer case projecting beyond the side wall of the inner case, an explosive within 100 the inner case, a top within the inner case inclosing the explosive, the side wall of the inner case projecting beyond the periphery of the top, the side walls of both of the cases turned inward over and water-proof cemented to the top, and a rail-attaching member connected to the case.

3. A fibrous water-proof non-flying railway signal torpedo, comprising a fibrous cup-shaped case, an explosive therein, a dome- 110

shaped top within the case and inclosing the explosive, the side of the case extending beyond the top and turned smoothly inward over the top and water-proof cemented thereto throughout its periphery to make a water-tight joint, and a rail-attaching member connected with the case.

4. A fibrous water-proof non-flying railway signal torpedo, comprising inner and outer fibrous cup-shaped cases, the side wall of the outer case projecting beyond the side wall of the inner case, an explosive within the inner case, a cover within the inner case and inclosing the explosive, the side walls of both cases turned over the cover with the

side wall of the outer case overlapping and extending beyond the side wall of the inner case to form a peripheral water-proof cement receiving cavity under the overlapping wall of the outer case, water-proof cement within the said cavity, for the purpose described, and a rail-engaging member carried by the case.

In testimony whereof I hereunto affix my signature in the presence of two witnesses. 25

FRANK DUTCHER.
